ENGINE REGULATING SYSTEM

Jerome D. Gleitz, Euclid, Ohio, assignor to The Marquette Metal Products Company, Cleveland, Ohio, a corporation of Ohio

Application September 1, 1944, Serial No. 552,335

4 Claims. (Cl. 123—140)

1

The principal object of this invention is to provide a simple, practical, self-contained, hydraulically acting, control system and mechanism useful for example in the positioning of fuel regulating elements of internal combustion engines of the type in which fuel is metered or supplied individually to the different cylinders. The above indicates the general object.

A further object is to provide a diesel engine injector control system and mechanism wherein each individual injector pump or its operating mechanism is actuated by positively acting force to regulate the amount of fuel pumped upon each injecting cycle without requirement of heavy mechanical connecting members and the like which often cause considerable trouble and are likely to result in derangement of the engine in case any of the injectors refuses to move.

A further object is to provide a diesel engine injector control in which the individual injectors are hydraulically operated for metering purposes and which system operates to effect isochronous control.

A further object is to provide a diesel injector control system including governor-maintained constant fluid pressure in each of a series of servomotors arranged to adjust respective injectors.

Other objects and features will become apparent from the following specification with particular reference to the accompanying drawings.

In the drawings:

Fig. 1 is a schematic view showing the system as applied to a multiple cylinder diesel engine, four units thereof only (four cylinders) being shown; Fig. 2 is a similar view showing generally the same arrangement but with a modified fluid distribution system for the injector adjusting servomotors, and Fig. 3 is a view similar to Fig. 2 showing a further modified fluid distributor system.

The embodiment of the present invention shown and described is for diesel engine regulation. Applicability to other practical uses will be apparent and are to be considered as coming within the scope of this invention.

Referring further to the drawings, Fig. 1 shows a governor mechanism, the case or body of which is indicated at 1. The governor except for the compensation-effecting servomotor A shown at the right, is essentially one of the standard types of governors currently manufactured by the assignee of this application. The arrangement of parts of the governor are given mainly by way of illustrating a suitable hydraulic relay governor adapted to serve in conjunction with the present system.

5 The governor mechanism as shown schematically in Fig. 1 comprises a fluid pump 2 connected to the engine to be served for operation by the engine, said pump operating through a reversible non-return valve system including ball elements 3 in suitable chambers to draw fluid from a governor sump 4 and deliver it into a receiving cylinder 5 of a hydraulic accumulator formed, for example, by a spring biased piston 6 operating in the cylinder and arranged to maintain constant pressure in the cylinder by virtue of a vent 7 in the cylinder wall leading to the sump 4.

10 Constant pressure maintained in the cylinder 5 is conducted through a passage 8 to and past a pilot valve bore 9 in which a valve plunger operates.

15 The pilot valve plunger 10 has a lower land 11 controlling a port 12 leading from the constant pressure line 8 to an upper portion 13 of the valve bore whenever the lower land 11 of the pilot valve plunger is moved downwardly out of the normal position in which it is shown. The constant pressure line 8 communicates with a space designated P in a cylinder bore 14 of the compensation-actuating servomotor A adjacent a relatively smaller area portion or side of a piston 15 in sealing contact with the cylinder wall.

20 The constant pressure against the lower face of the piston 15 obviously tends to raise the piston. The pilot valve bore portion 13 communicates through a passage 16 with the upper end portion R of the servomotor cylinder 14; and when constant pressure is admitted by the pilot valve to the passage 16, the servomotor piston 15 is moved downwardly by reason of the difference in area 25 of the upper and lower side of the piston. The piston has a trunk portion 17 slidable in a counterbore 18 which is vented to sump as at 19. The servomotor A is the preferred means of effecting stabilization of speed of the engine consequent upon imposed load changes as will be described later herein.

25 The pilot valve plunger 10 has an upper land 20 which normally blocks the valve bore 9 above the entrance therefrom to the passage 16, and when the pilot valve is moved upwardly from the position in which shown egress of constant pressure fluid from the passage 16 to sump is enabled through a lateral passage 21 normally closed by said upper land.

30 The pilot valve is controlled by a speed governor ball head mechanism indicated generally at 25 and comprising fly weights 26 with inwardly extending fingers arranged to bear upwardly upon an upper end portion of the pilot valve and in so doing acting against a speeder spring 27 bear-

35

55

The pilot valve is controlled by a speed governor ball head mechanism indicated generally at 25 and comprising fly weights 26 with inwardly extending fingers arranged to bear upwardly upon an upper end portion of the pilot valve and in so doing acting against a speeder spring 27 bear-

ing downwardly upon the pilot valve and reacting at its upper end against a speed adjustment element such for instance as a speeder plug 28 having suitable provision for adjusting it up and down in order to set the speed at which the engine is desired to operate.

The fly weights are suitably pivoted inside the ball head and the ball head is rotated by the engine when the latter is in operation as through the intermediary of a gear 24 connected to the ball head or forming a part of it. The governor operates as usual to adjust the pilot valve plunger and thereby cause movement of the piston 15 and simultaneously movement of corresponding piston elements of each of the set of injector adjusting servomotors 34, described below.

When the pilot valve plunger 10 is moved upwardly, as by increase of speed of the ball head acting through the fly weights, pressure from above the piston 15 is discharged to the sump of the governor through the passage 21. Such operation obtains for example when load on the engine is decreased, resulting in the attainment of a higher engine speed. Upon load increase the pilot valve is lowered from the position in which shown by the lessened centrifugal action of the fly weights and, more directly, by the force of the speeder spring; and thereupon the lower land 11 of the pilot valve plunger opens the port 12 to allow constant pressure fluid to be diverted through the valve bore portion 13 and passage 16 to the larger face of the piston 15. In governors such as shown operation of a single servomotor corresponding to servomotor A would cause adjustment of the fuel injector pump plungers of the various engine cylinders through mechanism connected to all the associated control racks. The specific purpose effected by the servomotor A in conjunction with the present invention will be described later herein.

Referring to the hydraulic injector adjusting mechanism shown at the right in Fig. 1 the injector adjusting servomotors 34 may all be assumed to be identical, one only being shown schematically in section. The constant pressure line 8 of the governor leads as at 8a (in by-passing relation to the servomotor A) to a distributor chamber 31 which is preferably a hollow block mounted on the governor case 1 but which, as would be indicated by Fig. 1, may be mounted for example on the engine in spaced relation to the governor. From the distributor chamber 31 suitable fluid conduits or fluid lines such as shown at 32 lead to the constant pressure spaces P of the servomotors 34. Similarly, the regulating pressure space 16 of the governor is connected as by a passage or conduits 16a, by-passing the servomotor A, to a distributor chamber 35 located similarly to the distributor chamber 31 or in the same block or body therewith as desired. From the chamber 35 individual lines 36 lead to the regulating pressure spaces R of respective servomotors 34.

In the particular arrangement of injector-adjusting differential pressure operated servomotors 32 illustrated in Fig. 1, the trunk portions 37 of the servomotor pistons 30, corresponding to the trunk portion 17 of the compensation effecting servomotor A (areas of pistons 15 and 30 being equal or in proportion), extend through suitable packing such as shown at 39 for connection with the injector racks 38 as by joints 37a of any suitable type. The racks 38 mesh with pinions 40 of the respective injectors to adjust the fuel input to the engine combustion chambers or cyl-

inders C as by turning suitable metering elements of the injectors (e. g. the injector pump plungers), between successive cycles of operation of the injector mechanisms.

When the governor calls for increased fuel supply to the engine the pistons 30 of the servomotors 34 are moved in the "fuel on" direction (e. g. to the right, Fig. 1) due to admission of constant pressure from the accumulator into the regulating fluid duct 16 by the governor pilot valve, and proportional transfer of regulating fluid pressure into the spaces R of the servomotors 34. Decreased fuel supply to the engine cylinders results from movement of the pistons 30 of servomotors 34 to the left (Fig. 1) by reverse operation of the governor—i. e. venting of regulating fluid to sump as previously described.

The fuel injectors of engine cylinders C can be of any suitable commercial type practically all of which as now used meter the fuel by reason of a turning movement of the injector pump plunger by an injector control rack.

The fluid distributor lines 32 and 36 would ordinarily be of varying length as determined by the distance from the distributor chambers 31 and 35 to the respective individual injector adjusting servomotors 34 supplied thereby. To compensate for different fluid friction effects due to such varying length of the distributor lines 32 and 35, the same may, if necessary, be of different cross sectional area, the longer ones being the larger. Alternatively individually adjustable valves 33a and 36a can be incorporated in the distributor lines, one pair for each servomotor 34.

As indicated above, the purpose of servomotor A of the governor is to effect prompt stabilization of engine speed following each load change. This stabilizing operation is generally known in speed governing as compensation. Compensation in the arrangement shown is initiated by each movement of the piston 15, concurrently with fuel adjusting movement of pistons 30, through a fluid pump comprising as shown a hollow fixed piston 42 slidable in sealed relation to a dead ended cylinder bore 43 in the trunk portion 17 of the piston 15. The lower end of the piston 42 communicates with a compensation fluid passage 44 leading to a cylinder bore 45 below the pilot valve plunger 10 and which may be formed by a downward continuation of the pilot valve bore 9. If desired, the speed of operation of the piston 15 in either direction may be adjusted by suitable fluid supply adjusting valves 22 and 23 in the associated duct portions 8 and 16.

Slidable within the cylinder 45 is a receiving compensation piston 46 connected as shown by a tension and compression coiled spring 47 anchored at its respective ends to the piston 46 and lower land portion 11 of the pilot valve plunger.

At some suitable point in the compensation fluid passage 44 is a restricted orifice such as 48 leading from said passage to sump. An adjusting screw 49 can be used to vary the size of the orifice as required by varying response of different engines to stabilization or compensation. Having in mind that downward movement of the piston 15 of servomotor A occurs whenever the pilot valve plunger is moved downwardly by the decelerating fly balls so as to call for a "fuel-on" or fuel increasing movement of the injector racks and that the reverse operation of the piston 15 obtains when the governor calls for decreased fuel movement of the fuel racks, compensation 75 is effected as follows. Downward motion of the

piston 15 pumps fluid in the passage 44 against the piston 45 and thereby resiliently opposes the downward movement of the pilot valve plunger such as necessary to admit constant pressure fluid to the distributor chamber 35 and thence to spaces R of the servomotor 34. When the piston 15 moves upwardly it tends to suck fluid from the passage 44 pulling the receiving compensation piston 46 downwardly thus resiliently opposing the action of the pilot valve in venting fluid from the regulating fluid passage 16 to sump. Each opposing action is temporary only since during stabilization of the engine speed the compensating fluid is returned to sump pressure through the restricted orifice 48. Any other compensating mechanism may be used. For example, the compensation fluid may be pumped directly by one of the servomotors 34 or all of the servomotors 34 may be connected to a common trunk line leading to the passage 44, and in case of either modification just suggested the servomotor A could be omitted.

Referring to Fig. 2, the governor case 1 shown in elevation may be assumed to represent a governor essentially the same as that shown schematically at the left in Fig. 1, the upper portion (speeder case 4a) communicating with the governor sump and the lower portion 1a constituting the power case of the governor into which the usual drive shaft 1b extends to operate the pump 2. In the arrangement shown, a hollow distributor block with separated spaces 31 and 35 is mounted on the side of the power case of the governor and said spaces communicate with the respective constant pressure fluid and regulating fluid spaces 8 and 16, respectively, as indicated and as previously described. The injector-adjusting servomotors 50, two only of the set being shown, may be essentially identical with the servomotors 34 previously described. However, the injector-rack-operating stems 51 of the pistons 30 of servomotors 50 are connected with the large end faces of the pistons so as to project out of the cylinders through the pressure spaces R instead of the spaces P of said servomotors. The pistons have their trunk portions 37 slidable in counterbore portions 52 of the servomotor cylinders, which counter bore portions may be connected to a common sump return line 53 shown as entering the governor sump as at 54. The common return line 53 enables any fluid which may slip past the trunk portions 37 during operation of the servomotors 50 to be returned to the governor case so as not to deplete the governor fluid supply. Individual supply lines to the different servomotors units 50 are indicated at 55 (four shown or indicated) for the constant pressure fluid distributor chamber 31 and at 56 for the regulating fluid distributor chamber 35. The individual lines leading to the constant pressure fluid and regulating fluid spaces P and R of the servomotor units 50 may be individually controllable as by valves 55a and 56a respectively for adjusting and synchronizing the speeds of operation of the servomotors when and if necessary. The arrangement of Fig. 2 operates the same as that of Fig. 1 except that by reason of the operating stems 51 of the servomotors 50 being connected to the larger end faces of the servomotor pistons, the fuel increasing and decreasing movement of the stems and associated fuel racks is, as indicated, the reverse of that described in connection with Fig. 1. The fuel racks 38 would accordingly be placed on a different side of the pinions 40 if the injectors

operated by the servomotors according to Fig. 2 turned in the same direction as those according to Fig. 1 for increasing and decreasing fuel.

The arrangement according to Fig. 3 differs from that of Fig. 2 in that common "rail" distributor lines 60 and 61 of adequate capacity convey the fluid from the distributor chambers 31 and 35, respectively, to all the servomotors 50, the constant pressure fluid spaces P and regulating fluid spaces R of the injector-adjusting servomotors 50 being connected in parallel to the lines 60 and 61 as by relatively short branch lines 62 and 63 all of which may be of the same length. The branch lines may be controllable as by valves 62a and 63a. The Fig. 3 arrangement would minimize the total length of fluid pipe required.

The connections between the operating stems 51 and the injector racks 38, as shown in Figs. 2 and 3, may comprise ball and yoke elements 65 or equivalent means for enabling the servomotor piston stems and the racks to be slightly out of alignment or parallelism, thus facilitating the mounting of the servomotors 34 on the engine. Any other suitable connections between the operating stems and the racks may be used such, for example, as will enable yielding movement of the racks 38 in one or both directions whereby hand control for the injector racks of the engine may be used as for starting and/or emergency shut-down purposes without requiring release of the fluid pressure in the servomotors 34, 50 of the governor.

While in both Figs. 1 and 2, for illustrative purposes only, the injector-adjusting servomotors 35 are shown very much oversize in proportion to the injector plunger adjusting pinions 40, the present system enables the individual injector rack adjusting servomotors, in a six cylinder engine for example, to be about one sixth of the power capacity, hence size, of the single servomotor ordinarily used in connection with governors such as schematically shown herewith and adapted to regulate six cylinder engines through the usual heavy and more or less complicated mechanical connections.

Thus, in addition to effecting positive synchronous control of the various injectors while eliminating the necessity for heavy connecting parts, numerous joints, pivots, etc. and other power losses such as characteristic of mechanical connections and special adaptations to different types of engines, the present system greatly reduces installation costs and service difficulties.

While in the above description the manner of obtaining isochronous operation of the engine is emphasized, speed droop for paralleling adjustment of engines connected, as electrically, to a common load can be obtained for example by connecting the piston 15 of the compensation-effecting servomotor A (or one of the injector regulating servomotors 34 or 50) to suitable mechanism (not shown) for adjusting the speeder spring 27 so as automatically to slack off on said spring a slight amount in proportion to the degree of regulating servomotor movement in the "fuel on" direction. Any convenient arrangement may thus be used when speed droop is desired.

It will also be apparent that the present engine control system and mechanism is adaptable to practically all types and designs of governors through appropriate modification.

I claim:

1. In the combination comprising a plurality of servomotors each adapted to operate a fuel

injector of an engine and a hydraulic relay governor having a pilot valve controlling fluid which in turn effects fuel regulating operation of the servomotors; the arrangement comprising a piston and cylinder mechanism associated with the governor and operable independently of the aforesaid servomotors, being subjected by the pilot valve to the same fluid influence as are the servomotors but in parallel-connected arrangement relative thereto, and a hydraulic compensation system operated by said piston and cylinder mechanism to force fluid into restraining relationship to the pilot valve during speed changes.

2. An individual cylinder fuel control mechanism for internal combustion engines comprising a set of fuel regulating servomotor piston and cylinder units individually associated with the cylinders and each having a large and a small piston area, a hydraulic relay governor for the engine having a constant pressure fluid source, said governor comprising a pilot valve and speed responsive means connected therewith, a servomotor piston and cylinder unit on the governor having relatively large and small piston areas of approximately the same ratio as in said set of servo-motor units, conduit means connected with said pressure source and continuously maintaining fluid in operating contact with all the smaller piston areas, other conduit means controlled by the pilot valve in a manner normally to maintain said constant pressure fluid trapped in operating contact with all the larger piston areas, the pilot valve being movable in opposite directions from an equilibrium position to replenish and vent said fluid to and from the respective areas in response to engine speed changes whereby to cause movements of the pistons in respective opposite direc-

tions solely by fluid from said source, and a compensation fluid pumping system operated by said servo-motor of the governor and automatically acting on the pilot valve to restrain each of its valving movements.

3. The mechanism according to claim 2 wherein the servo-motor of the governor has adjusting valve means arranged to control the rate of flow of replenishing and venting fluid thereto and therefrom independently of the rate of replenishing and venting of fluid to and from the engine-cylinder-associated servo-motors in consequence of pilot valve movement.

4. The mechanism according to claim 2 wherein one of the set of engine-cylinder-associated servo-motors has an adjusting valve means for controlling the rate of flow of fluid in respect thereto independently of the rate of flow in respect to another servo-motor of said set.
